[57] CLAIM

The ornamental design for a slat wall back panel desk, as shown and described.

DESCRIPTION

FIG. 1 is a front, top and right side perspective view of a slat wall back panel desk showing my new design;

FIG. 2 is a rear, top and left side perspective view thereof;

FIG. 3 is a front, top and left side perspective view of another form of the slat wall back panel desk; and,

FIG. 4 is a rear, top and right side perspective view thereof.

The bottom of the desk is plain and unadorned.
